ALL-METAL POWER TABLE FOR SEWING MACHINES

Daniel H. Chason, Elizabeth, and Franklin A. Park, Jr., Westfield, N. J., assignors to The Singer Manufacturing Company, Elizabeth, N. J., a corporation of New Jersey

Substitute for abandoned application Serial No. 147,624, June 11, 1937. This application May 31, 1939, Serial No. 276,634

9 Claims. (Cl. 311—13)

This application is a continuation of our application Serial No. 147,624, filed June 11, 1937.

This invention relates to sewing machine power-tables and it has as its primary object to provide an all-metal power-table which will be rigid in construction; which will be relatively quiet during operation of the sewing machines thereon; which will not be affected by climatic conditions; which will be splinter-proof; which will be readily adaptable for sewing machines of various sizes; which will not feel cold to the touch of the operator's arms; and which may be manufactured and installed at a minimum of expense.

With the above and other objects in view, as will hereinafter appear, the invention comprises the devices, combinations and arrangement of parts hereinafter set forth and illustrated in the accompanying drawings of a preferred embodiment of the invention, from which the several features of the invention and the advantages obtained thereby will be readily understood by those skilled in the art.

In the accompanying drawings Figure 1 is a front elevation of a sewing machine power-table embodying the present invention.

Figure 2 is a plan view of the front portion of Fig. 1.

Fig. 3 is an enlarged vertical sectional view taken substantially on the line 3—3 of Fig. 2, with the upper portion of the sewing machine broken off.

Fig. 4 is a right end elevation of the power-table illustrated in Fig. 1.

Fig. 5 is an enlarged vertical sectional view taken substantially on the line 5—5 of Fig. 2.

Fig. 6 is an enlarged sectional view taken substantially on the line 6—6 of Fig. 2 showing means for supporting the sewing machine independently of the table-top.

Fig. 7 is a sectional view taken on the line 7—7 of Fig. 2.

Fig. 8 is a detail plan view of an adjustable framework for supporting a sewing machine and a power-transmitter.

Fig. 9 is a detail plan view of a power-transmitter supporting plate, later to be described.

Fig. 10 is a detail plan view of one of a plurality of interchangeable sheet-metal table-tops adapted selectively to be applied to the improved power-table and illustrating so-called "wrinkle" finish thereon.

Fig. 11 is an enlarged sectional view taken on the line 11—11 of Fig. 10.

Fig. 12 is a view of a plurality of interchange-

able cross-braces for the supporting framework shown in Fig. 8.

Fig. 13 is an enlarged detail sectional view taken substantially on the line 13—13 of Fig. 2, showing one of the machine hinges and the machine cushioning means which normally maintains the hinge parts out of contact with each other when the machine is in its operative position.

Fig. 14 is a detail view showing means for supporting one of the motor-controlling switch boxes from the sewing machine supporting framework.

Referring more specifically to the drawings, this invention is disclosed as embodied in a sewing machine power-table comprising spaced H-shaped leg-sections L each formed of a pair of upright primary leg-members 1, a cross-brace 2 connecting said primary leg-members, secondary leg-members 3 adjustably secured in the upper ends of the primary leg-members, and a cross-rail 4, or 4^a, secured to the upper ends of the secondary leg-members. The parts above mentioned preferably are made of sheet-metal channel bars, U-shaped in cross-section, and may be constructed and assembled as disclosed in United States Patent to Eames, No. 1,695,419, Dec. 18, 1928.

Arranged horizontally and connected at its opposite ends to the cross-rails 4 and 4^a of adjacent leg-sections, is a supporting framework F, shown most clearly in Fig. 8. This framework is adapted to support a sewing machine S, a power-transmitter P for driving the machine, and a switch-box 23 which carries a suitable switch for controlling the electric motor of the power-transmitter.

In Figs. 1 and 4 of the drawings there is illustrated the so-called double trough-type power-table, i. e., a power-table designed to support a sewing machine at each side thereof and provided between the machines with a work-receiving trough T. It is to be understood however that the invention is also adaptable to single power-tables, i. e., power-tables designed to support sewing machines only on one side thereof. Inasmuch as the parts for supporting the sewing machine and its driver are the same, whether used on a single or double table, a detail description of one will suffice. Likewise only one section of the table will be shown and described, it being understood that as many of these sections as desired may be coupled together.

The framework F is preferably made of channel-iron and comprises a front rail 5, having inturned end-portions 5^a adapted to be fixedly

secured to the cross-rails 4 and 4^a, as by bolts 6, and a rear rail 7, having end-portions 7^a adjustably secured at one end to the cross-rail 4^a by a bolt 8 (see Fig. 7) and at its opposite end, by a bolt 9, (see Fig. 6) to a channel-iron bracket 10 fixedly secured to the cross-rail 4 and to the front rail 5. To the rails 5 and 7, intermediate the ends thereof, there is adjustably secured a cross-brace 11, also of channel-iron. As shown most clearly by Fig. 8, the rails 5 and 7, the cross-brace 11 and the bracket 10 constitute a rectangular frame, designated as *f*, adapted to receive the bed of a conventional sewing machine. Referring to Figs. 3 and 13, it will be seen that the bed *b* of the sewing machine rests upon cushions *c* supported upon brackets 12 secured to the cross-brace 11 and the bracket 10 and wholly out of contact with any metal portion of the frame or table-top.

As above mentioned, the rail 7 is adjustably secured to the cross-rail 4^a and to the bracket 10. This is effected by providing a series of bolt-holes 8^a in the rail 4^a (see Fig. 7) for the bolt 8 and a corresponding series of holes 9^a in the bracket 10 (see Fig. 6) for the bolt 9. Likewise the cross-brace 11 is adjustable lengthwise of the rails 5 and 7, a series of bolt-holes 13^a (see Fig. 3) being formed in each rail to receive the bolts 13 which secure the brace to the rails. By reason of these adjustments the size and shape of the rectangular machine supporting frame *f* may be varied to accommodate various sizes of machine beds. When it is desired to vary only the length of the machine supporting frame *f* this may be done by shifting the cross-brace 11 lengthwise of the rails 5 and 7. Should it be desired to vary the width of the frame *f*, this is effected by adjusting the rail 7 on the cross-rail 4^a and on the bracket 10 and substituting a different cross-brace 11 of a length corresponding to the space between the rails 5 and 7, as shown in dotted lines in Fig. 8. From the foregoing it will be perceived that the sewing machine is supported by the metal framework comprising the members 5, 7, 10 and 11.

To permit the sewing machine to be tipped backwardly for oiling, inspection or repair, the machine bed is provided with a pair of hinge elements 14 adapted to cooperate with a pair of mating hinge elements 15 secured to the rail 7. When the machine is in its normal working position these complementary hinge elements are maintained out of contact with each other, as shown in full lines in Fig. 13, the machine resting wholly upon the cushions c. Therefore vibration in the sewing machine is not transmitted to the supporting framework through the hinges, but is absorbed by the cushions c.

Secured upon the tops of the cross-rails 4 and 50 4^a, and held in place by cleats 16, is a sheet-metal table-top 17, having, at its forward side, a down-turned flange 17^a terminating in a rolled edge 17^b. This rolled edge increases the rigidity of the table-top and forms a smooth edge for 65 the protection of the operator. As shown by Figs. 2 and 10, the table-top is formed with a rectangular opening 17^c of a shape and size to receive the bed b of the sewing machine. The opening is slightly larger than the machine bed 70 so that there is no contact between the two. The table top also is formed with slots 17^d and 17^e affording passages for the belt 18 which connects the sewing machine with the power-transmitter P. At its ends, the table-top is provided with 75 semi-circular notches 17^f adapted to partially

surround bolts 19 which pass through the cleats 16, cross-rails 4, 4^a and plates 20, which engage the under side of the cross-rails, to clamp the parts together. The rear side of the table-top is formed as a downturned flange 17^a (see Fig. 5) to which one edge of the sheet-metal work-trough T is secured, as by bolts 21. 5

As shown in Fig. 4, the lower edges of the sheet-metal end walls t' of the trough are spaced slightly above the bottom wall t^2 thereof, thus affording an aperture t^3 through which dirt, lint, etc. may be brushed when cleaning the trough.

Interposed between the under side of the table-top and the machine-supporting framework F are a plurality of vibration-absorbing cushions 22. 15 These cushions serve to support the mid-portion of the table-top and also to prevent such vibration of the table-top as otherwise might produce a resonance or drumming effect.

It is to be understood that any one of a plurality of sheet-metal table-tops, each cut out to suit a specific sewing machine, may be secured selectively to the cross-rails 4, 4^a. In addition to supporting the sewing machine, the framework F also supports the power-transmitter P, the switch-box 23 housing a switch 23^a for controlling the electric driving motor of the transmitter, and the knee-control for the presser-foot lifting mechanism of the sewing machine. Straddling the rail 7 of the framework F is a sheet-metal saddle 24 having horizontally disposed feet 24^a to the under side of which is adjustably secured, by bolts 24^b, a power-transmitter supporting-plate 25 to which one portion of the power-transmitter frame p is secured by bolts 26 passed through apertures 25^a in the plate 25. Another portion of the power-transmitter frame is secured to a bracket 26^a fixed to the bracket 10, which forms a part of the framework F. As shown most clearly in Fig. 9, the power-transmitter supporting-plate 25 is provided with a plurality of sets of bolt-holes x, y and z adapted to receive the bolts 24^b. This permits adjustment of the rail 7, and the saddle 24 carried thereby, laterally relative to the plate 25 which is permanently secured to the non-adjustable power-transmitter. The power-transmitter may be controlled by a conventional manually actuatable treadle mechanism designated generally as m.

The sewing machine is provided with a presser-foot *s* and lifting mechanism therefor, designated generally as *t*, and knee-controlled means is carried by the framework *F* for actuating that mechanism. This means comprises a rock-shaft *27* journaled, adjacent one end, in a bearing formed in a hanger consisting of a down-turned portion *25^b* of the transmitter supporting-plate *25*. Adjacent its other end, the rock-shaft *27* is journaled in a bearing provided by a hanger *28* secured to the front rail *5* of the framework *F*. A knee-treadle *29* is secured to the rock-shaft, intermediate its ends, and serves as means to oscillate the shaft. Also secured to the rock-shaft, is an arm *30* (see Fig. 3) adapted to act upon one end of a spring-biased lever *31* fulcrumed, at *32*, on a bracket *33* depending from the under side of the sewing machine bed-plate *b*. At its opposite end the lever *31* is connected with the presser-foot lifting mechanism *t*. Thus, by actuating the knee-lever *29*, the operator may effect raising and lowering of the sewing machine presser-foot *s*. An arm *34*, secured upon the rock-shaft *27* adjacent the bracket *28*, is adapted to engage an abutment *35* provided by said bracket, and thereby limits the oscillatory movement of the rock-shaft *27*.

motion of the rock-shaft in its presser-foot lifting movement. It will be noted that the length of the rock-shaft 21 is materially greater than the distance between its supporting hangers 25^b and 5 28. Therefore a substantial relative lateral adjustment may be made between the channel irons 5 and 7 without withdrawing the shaft from its supporting bearings.

The switch-box 23, which carries the switch 10 for controlling the flow of current to the motor of the power-transmitter, also is carried by the front rail 5 of the framework F. As shown by Figs. 1 and 14 the switch-box has attached to its upper end, by bolts 23^b, an angle-bracket 36, 15 secured to the rail 5 by bolts 37.

As hereinbefore stated, one of the objects of this invention is to provide a metal power-table which will not feel cold to the operator's arms. This has been attained by forming the table-top 20 with a roughened upper surface providing an infinite number of relatively raised and depressed portions. With a surface of this nature there is obtained, between the arms of the operator and the table, what may be termed "point contacts" 25 as distinguished from a surface contact as when touching a smooth surface. These point contacts absorb only a small amount of heat from the operator's arms and therefore a sheet-metal table having this type of surface has a decided feeling 30 of warmth as compared with the relatively cold feeling of smooth sheet-metal at the same temperature.

A surface of this nature may be obtained in various ways but preferably it will be obtained by 35 coating the metal with a paint adapted, in its drying operation, to produce a rough, irregular or so-called "wrinkle" finish. This finish, which heretofore has been used only for ornamental purposes, may be produced by coating the metal 40 with a special type of commercial varnish, enamel or japan so made that when heat is applied thereto the surface dries first and further drying causes the coating to wrinkle, all as disclosed in U. S. Patent to F. B. Root, No. 1,689,892, Oct. 30, 45 1928. One commercial brand of paint which may be used for this purpose is "Damaskene" manufactured and sold by Flood & Conklin Co., of Newark, N. J. In using this product satisfactory results are obtained by spraying the sheet-metal 50 with the paint and then baking it for about two hours at a temperature of approximately 350° F.

The resulting product, as illustrated in Figs. 10 and 11, comprises a myriad of hills w and intervening dales w'. The apexes of the hills afford 55 the point contacts hereinbefore mentioned, which have a relatively low coefficient of heat conductivity.

From the foregoing it will be perceived that this construction provides an all-metal power-table for sewing machines which attains all of the objects of the invention, and which therefore affords great advantages over the combined wood and metal power-tables heretofore provided.

Having thus set forth the nature of the invention, what we claim herein is:

1. In combination, a sewing machine power-table comprising spaced leg-members, a horizontally disposed framework supported at its opposite ends by said leg-members, one element of 70 said framework being horizontally adjustable relative to another element thereof, a table-top supported by said leg-members and provided with an aperture adapted to receive a sewing machine, a sewing machine mounted on said framework within said aperture, and a power-transmitter

adjustably secured to the adjustable element of said framework and operatively connected with said sewing machine.

2. In combination, a sewing machine power-table comprising spaced leg-members, a horizontally disposed metal framework supported at its opposite ends by said leg-members and comprising an end-bracket and front and rear rails secured thereto, one of said rails being adjustable laterally, a metal table-top supported by said 10 leg-members and provided with an aperture adapted to receive a sewing machine, a sewing machine mounted on said framework within said aperture, an electric power-transmitter adjustably supported by said bracket and the adjustable 15 one of said rails, and operatively connected with said sewing machine, and manually actuatable means carried by said framework for controlling said power-transmitter in all of its adjusted positions. 20

3. In combination, a sewing machine power-table comprising spaced supports consisting of vertically arranged legs and horizontally disposed cross-rails supported thereby, a horizontally disposed framework, comprising relatively 25 adjustable members, supported at its opposite ends by said cross-rails and consisting of transversely arranged and adjustably connected channel-irons, a table-top supported by said cross-rails and provided with an aperture adapted to 30 receive a sewing machine, a sewing machine mounted on said adjustable framework within said aperture, and a power-transmitter supported by said framework and operatively connected with said sewing machine. 35

4. In combination, a sewing machine power-table comprising spaced supports consisting of upright legs and horizontally disposed cross-rails supported thereby, a horizontally disposed metal framework supported at its opposite ends 40 by said cross-rails, a table-top supported by said cross-rails and provided with an aperture adapted to receive a sewing machine, a sewing machine mounted on said framework within said aperture, said framework being adjustable in transverse 45 directions to accommodate sewing machines of various shapes and sizes, and an electric power-transmitter supported by said framework and operatively connected with said sewing machine.

5. A power-table comprising spaced leg-members, a horizontally disposed metal framework supported at its opposite ends by said leg-members and adapted to support a sewing machine, one element of said framework being horizontally adjustable relative to another element thereof, 55 a table-top supported by said leg-members and provided with an aperture adapted to receive a sewing machine supported on said framework, and a power-transmitter adjustably secured to the adjustable element of said framework and 60 adapted to be operatively connected with a sewing machine carried by said framework. 50

6. An all-metal power-table for sewing machines comprising spaced metal leg-members, a horizontally disposed fabricated metal framework supported by said leg-members and adapted to support a sewing machine, said framework comprising a first channel-iron extending lengthwise of the table and connected at its opposite ends to said leg members, a transverse channel-70 iron constituting a bracket having one end connected to said first channel-iron and having its other end offset and secured to one of said leg-members, a second channel-iron arranged substantially parallel with said first channel-iron 75

and having one end connected to one of said leg-members and its other end secured to said transverse channel-iron, a transverse brace connecting said channel-irons intermediate their ends, a sheet-metal table-top secured upon said leg-members and provided with an aperture adapted to receive a sewing machine, and a power-transmitter suspended from said framework and adapted to be operatively connected with a sewing machine supported upon said framework.

7. A power-table as set forth in claim 6 in which the power-transmitter is secured at one end to a bracket carried by said transverse channel-iron and at its other end to a saddle supported by said second channel-iron.

8. A power-table as set forth in claim 6 in which said first channel-iron is permanently secured to said leg-members and in which said second channel-iron is adjustably secured to one of said leg-members and to said transverse channel-iron thereby to accommodate sewing machines of various widths.

9. A power-table as set forth in claim 6 in which the transverse brace is adjustably mounted on said channel-irons, to accommodate sewing machines of various lengths.

DANIEL H. CHASON.

FRANKLIN A. PARK, JR.
